KARL R. SCHUSTER, OF BROOKLYN, NEW YORK.

MONOLITHIC FLAT SLAB.

1,417,774.

Specification of Letters Patent. Patented May 30, 1922.

Application filed June 1, 1918. Serial No. 237,700.

To all whom it may concern:

Be it known that I, KARL R. SCHUSTER, residing at the city of New York, borough of Brooklyn, county of Kings, and State of New York, have invented a certain new and useful Monolithic Flat Slab, of which the following is a specification.

This invention pertains to a monolithic flat slab for building constructions wherein 10 the slab as an entirety is supported on columns, said slab being free from support along its several sides or margins, the latter form of support being characteristic of ordinary floor constructions of a composite 15 nature.

It is well known to construction engineers that composite flat slabs supported solely by columns are subjected to load stresses differing widely in character from the stresses incurred in composite plates the margins of 20 which are supported by walls and beams.

In the present invention, the flat slab is free from the support afforded by beams and girders, finding its support through the 25 medium of columns the couples of which are spaced equi-distantly apart, for which reason I stiffen the slab by a reinforce known in the art as a two-way reinforce, the same comprising two belt courses of rods or bars 30 located below the neutral axis of the slab and in the tension chord thereof, the rods of one belt course crossing at a right angle the rods of the other belt course, and the two courses of rods running diagonally to 35 the center lines between and through the columns.

The composite flat slab is reinforced substantially equally in both directions by the belt courses of rods, the same affording a 40 simple construction economical in the use of steel, but experience shows that a two-way reinforced slab of the character under consideration when supported by columns coupled in pairs spaced equi-distantly is subjected to greater stresses along the lines of 45 the diagonals between opposite couples of the adjoining pairs of columns, for the reason that the distance is greater on the diagonals between opposite couples of the 50 adjacent pairs of columns than it is between the columns composing the couples or pairs.

Accordingly, this invention embodies a distribution of the steel or of the materials entering into the construction of the slab in 55 such a manner as to take care of the diagonal

stresses in a two-way reinforced slab. This object is attained by using steel in greater quantity along the diagonals, or the same end may be attained by the use of an increased volume of masonry or of stronger 60 masonry, or any combination of the steel and masonry, to thereby take care of those parts of the flat slab which are subjected to the greater stresses.

In a two-way reinforced flat plate or slab 65 the use of two crossing belt courses of rods each utilizing the same amount of steel, it is apparent that the resulting slab is theoretically equally strong in tension in any direction. Such reinforced slab is thus well 70 adapted for resisting load stresses when distributed equally, but the use of a slab in connection with columns the couples of which are spaced equally develops areas or strips of material which are weaker along 75 the lines of the diagonals between the columns than strips or areas along the center lines between said columns. To secure the necessary stability along the diagonal areas the quantity of material is increased to a 80 substantial extent along the areas extending diagonally between the columns.

Other functions and advantages of the invention will appear from the following description taken in connection with the drawings, the latter illustrating several embodiments of the invention, wherein—

Fig. 1 is a plan view illustrating a monolithic flat slab embodying this invention, the dotted lines illustrating in part the equi-distant spacing of the columns coupled in pairs, and certain lines indicating the margins of the slab extending through the center line of the columns.

Fig. 2 is a plan view of another embodiment of the invention illustrating a single column and the means for reinforcing the slab associated with said column.

Fig. 3 is a plan view of another embodiment of the invention illustrating another 100 form of reinforce.

Figs. 4 and 5 are vertical sections in the planes of the dotted lines 4—4 and 5—5, respectively, of Figs. 2 and 3.

Fig. 6 is a plan view illustrating another 105 embodiment of the reinforcing means in connection with the columns and the slab.

Fig. 7 is a vertical section taken through a slab on a line extending diagonally from one column of a pair or couple to the oppo- 110

site column of an adjoining pair or couple to show the means for increasing the strength of the slab on the diagonal line between the specified columns.

5 Figs. 8 and 9 are plan views of other embodiments of the invention wherein the rods or bars are positioned in the slab to the end that the unit stresses will be substantially equal throughout the slab.

10 The flat slab A in Fig. 1 is composed of concrete, or concrete and tile, said slab being reinforced by rods B C extending in two directions throughout the area of the slab. As is usual in structures of this class, the 15 slab is free from the supports afforded by beams or walls along the margins or several sides of the slab, but it is supported solely by columns two pairs or couples of which are indicated in dotted lines at D, E, F, G, as 20 a result of which organization and relation the slab under load stresses simulates the action of a flat plate.

As shown by the lines extending between the columns in Fig. 1, the couple or pair of 25 columns D E are spaced equidistantly from the adjacent couple or pair F, G, but the distance between the center of columns D G or E F being on the diagonals, exceeds the 30 distance between any two columns composing a couple or pair.

The rods B constitute a belt course extending throughout the area of the slab, whereas the other rods C form a second belt course also extending throughout the area of 35 the slab. Said rods B C are of equal cross section individually, and they are embedded in the material of the slab below the neutral axis and in the tension chord thereof. All the rods are arranged diagonally to the 40 lines extending centrally through the columns so as to cross the lines indicating said center lines, and thus the diagonal rods are continuous through a panel supported by four columns so as to extend beyond the 45 margins of said panel and into the panels adjacent to the panel bounded by the four center lines.

The rods B of one belt course cross or intersect with the rods C of the other belt 50 course, and all said rods are spaced equidistantly, which relation of the rods provides spaces adapted for the reception of hollow tiles as disclosed in my prior Patent No. 1,134,164, although it is to be understood that the slab may be composed solely 55 of concrete reinforced in accordance with this invention.

The slab reinforced by the crossing belt courses of rods embodies a construction 60 wherein the areas extending parallel to the central lines between the columns are reinforced to carry the load stresses without fracture, but experience shows that the weakest areas of such a reinforced slab are on the 65 diagonal lines between the couples of equi-

distantly spaced columns. Accordingly, in this invention I dispose or organize the steel to take care of the greater stresses developed on the longer diagonal lines between the columns, and to this end I employ either of the 70 several constructions depicted in the drawings.

In Fig. 1, the rods B' C' extending on the diagonals are of increased cross section or much heavier than the rods B C in the two 75 intersecting belt courses of rods comprising in part the two-way reinforcement. Thus there is a group of heavier rods B' extending between the columns D G, and another group of heavier rods C' extending between 80 the columns E, F, the rods B', C' being in the lower chord of the slab and parallel to the rods B C respectively, said heavier rods B' C' constituting a part of the reinforcement the remainder of which is afforded by 85 the lighter rods B C.

All the rods run diagonally through the slab, and the heavier rods B' C' cross the enlarged capitals of the columns D E F G, whereby the slab is stiffened on the longer 90 diagonal lines between the columns so as to take care of the increased load stresses.

In addition to the rods B' C' in the lower chord to serve as tension members, the slab is reinforced by embedding a mat or 95 grill work of rods in the material over each column, said mats being indicated at H. The mat or grill is positioned in the upper chord of the slab, and the area of the mat or grill exceeds the cross section of the column, whereby said mat or grill operates to 100 take care of the negative bending moment and of the vertical shear present in the slab at the areas adjacent the column.

The slab A of Fig. 2 includes the two- 105 way reinforcement B C together with means for stiffening the slab in the areas of the diagonals between equidistantly spaced columns. Instead of using heavier rods in the belt courses along the diagonals, the rods 110 are of uniform cross section throughout, but the rods along the diagonals between the columns are grouped or crowded more closely together at B² C², and in the diagonal areas between the columns the slab is made of 115 greater depth so as to bring the steel lower down, thus resulting in an effective stiffening of the slab along the diagonal areas. The rods B² C² extending across the columns are bent upwardly over the columns 120 and additional rods H' are used for taking care of the negative bending moment.

In the slab A of Figs. 3 and 5 the predominating element of a stiffer reinforce 125 on the diagonals between the columns is disclosed, but in this example of the invention the two-way reinforce afforded by the rods B C is supplemented by the use of groups of rods B³ C³ on the diagonals between the columns, the rods in each group B³ C³ being 130

graduated in thickness toward the central diagonal line, the middle rods of the diagonal group being the heavier and the rods decreasing from the middle rod B^3 or C^3 to

5 the other rods of the two way reinforce B C. A mat or grill H is used in the upper chord of the slab and positioned over the column, and said slab is increased in depth at b in the areas adjacent and over the column in order

10 to take care of the negative bending moment and the increased vertical shear.

The flat slab shown in Fig. 6 of the drawings illustrates the two-way reinforcement comprising two crossing belt courses of rods

15 B C extending parallel to the centre lines between the columns instead of diagonally.

To secure the effect of increased stiffness on the diagonals between the columns I employ short rods or bars B^4 C^4 , one series B^4

20 of which extends across the diagonal line between the columns D G whereas a second series C^4 extends across the diagonal line between the other columns E F. These short rods B^4 C^4 are parallel to the rods B C re-

25 spectively to constitute diagonal belts which add materially to the stiffness of the slab on the diagonals between the columns, and said rods are positioned in the material of the slab below the neutral axis and in the ten-

30 sion chord thereof. Over the columns are the mats or grills H positioned in the upper chord of the slab.

As hereinbefore indicated, the two belt courses of rods crossing each other through-

35 out the area of the slab provide spaces between the rods for the reception of tile blocks as shown in Fig. 7. The blocks I may be equal in height to the depth of the slab so that the blocks cooperate with the rods

40 B C and the concrete beams, but in the areas of the slab extending in the diagonals between the columns I prefer to use heavier rods B' C' as in Fig. 1 and to use tile blocks

45 I', the height of which is less than that of the blocks I, thus enabling me to increase the thickness of the concrete material at c in the diagonal areas between the columns, whereby a strong slab reinforced at the lines of greatest stresses is obtained.

50 Although I have described the flat slab as especially adapted for concrete buildings, it is to be understood that the monolithic structure is equally well adapted for foundations, retaining walls, and the decks of ships, etc.

In the embodiment of the invention as heretofore described the columns are equidistantly spaced to the end that lines extending through the centers of said columns form

55 the boundaries of squares, the stresses on the slab along the four boundary lines being equal and being taken care of by the two series of crossing rods, whereas the stresses on the longer diagonals between two columns

60 of adjacent pairs or couples are taken care

of by increasing the heaviness of the steel according to the several ways herein disclosed.

The principle of the invention is applicable, also, to flat slabs wherein the columns 70 are spaced for the center lines to produce oblong panels instead of square panels, the former spacing being shown in Figs. 8 and 9, thus resulting in an organization wherein the slab is subject to stresses on lines unequal in length in three respects; i. e. two short lines between the four columns D F and E G as at 1-1 and 2-2; two longer lines between the columns D E and F G at 75 3-3 and 4-4, and two other still longer lines, one extending diagonally between columns D G, and the other extending diagonally between columns E F, the lines 1-1, 2-2, 3-3, 4-4 forming the boundaries of an oblong panel.

The steel in the oblong panels of Figs. 8 and 9 is distributed to perform the function of taking care of unit stresses to a substantially equal extent throughout the area of said oblong panels.

In Fig. 8, the crossing bars B C are arranged at angles other than right angles so that the spaces formed by the crossing bars are of rhomboidal form, said bars B C extending diagonally across the boundary 95 lines of the oblong panels supported by the spaced columns. Said bars B C stiffen the slab on the lines 1-1, 2-2, 3-3 and 4-4 so as to preclude fracture along the short lines 1-1 and 2-2 and on the longer lines 3-3 and 4-4 between the columns, the crossing of the rods B C at such angles as will produce rhomboidal figures tending to so group the rods along the two sides unequal in length as to take care of such stresses. In 100 view of the fact that the diagonals between the columns in an oblong panel are considerably longer than either of the lines along the boundaries of such panels, I employ belts of heavier rods B^5 C^5 along the diagonals 110 between columns D G and E F, said heavier rods B^5 and C^5 being parallel to the rods B C respectively and each belt course of heavier rods composing a part of the reinforcement afforded by one series of rods B or C. It 115 should be stated that the heavier belt course B^5 C^5 between the columns are extended throughout the area of the slab so as to cross other similar rods of other panels in a manner for said heavier belt courses of rods 120 B^5 C^5 to produce figures of rhomboidal shape, thus contributing to the stiffening of the slab throughout the area thereof by the economical use of steel.

The reinforce illustrated in Fig. 9 for an 125 oblong slab embodies the two belt courses of rods B C crossing each other at right angles to result in square spaces adapted for the reception of tile blocks, the rods B being parallel to the longer lines 3-3 and 4-4 130

- at two sides of the oblong whereas the rods C are parallel to the shorter lines 1—1 and 2—2 at the two remaining sides of the oblong. It is preferred, however, to use belt courses of heavier rods B⁶ between the columns D E and F G in order to take care of the stresses along the longer lines 3—3 and 4—4. On the diagonals between the columns D G and E F the steel is increased by the use of two belt courses of short rods, one belt course of short rods B⁷ being parallel to rods B and extending diagonally between columns D G and E F, whereas the other belt course C⁷ of short rods are parallel to rods C and extend diagonally between columns D G and E F, the diagonal belt courses of short rods B⁷ and C⁷ taking care of the stresses along the lines of the longer diagonals between the columns.
- 20 It is to be noted that the rods described are in the lower (tension) chord of the slab, below the neutral axis thereof, but I utilize the grill or mat G in the upper chord of the slab over each column for taking care of the increased vertical shear in the area of the slab adjacent the column.

30 The columns may be composed of concrete reinforced by steel rods as usual, or such columns may be composed of steel and the slabs supported thereon as disclosed in one of my prior applications.

Having thus fully described the invention, what I claim as new, and desire to secure by Letters Patent is:—

- 35 1. A monolithic flat slab free from support along its several margins and sustained by columns the couples of which are spaced equidistantly embodying at least two belt courses of rods positioned in crossing relation and in the material of the slab substantially below the neutral axis thereof and with the individual rods of said belt courses running diagonally to the center lines extending between the pairs of columns, those 40 rods of each belt course which are positioned along the diagonal lines between opposite columns of adjacent pairs of columns being increased in quantity with respect to other rods of the same belt course extending in other areas of the slab, thereby producing in the slab diagonally to the columns distinctive areas the strength of which exceeds the strength in other areas of the slab.

55 2. A monolithic flat slab free from support along its several margins and sustained by columns the couples of which are spaced equidistantly embodying at least two belt courses of rods positioned in crossing relation and in the material of the slab substantially below the neutral axis and in the tension chord thereof and with the individual rods of said belt courses running diagonally to the center lines extending between the pairs of columns, the areas of the slab extending diagonally between oppositely

placed columns of adjacent pairs being increasingly stiffened and exceeding in strength the areas extending between the columns on the center lines thereof as well as other portions of the slab.

3. A monolithic flat slab free from support along its several margins and sustained by columns the couples of which are spaced equidistantly embodying at least two belt courses of rods positioned in crossing relation and in the material of the slab substantially below the neutral axis and in the tension chord thereof, the individual rods of each belt course being positioned diagonally to the center lines between the columns and the rods of one belt course crossing the rods of the other belt course, those rods in each belt course which extend between diagonally opposite columns of adjacent pairs exceeding in cross sectional area the rods in the remaining area of the slab, whereby the slab is increasingly stiffened in those areas which extend diagonally between oppositely placed columns of adjacent pairs and which diagonally extending and increasingly stiffened areas exceed in length the areas between the columns on the center lines thereof.

4. A monolithic flat slab free from support along its several margins and sustained by columns the couples of which are spaced equidistantly embodying at least two belt courses of rods positioned in crossing relation and in the material of the slab substantially below the neutral axis and in the tension chord thereof, the individual rods of each belt course being positioned diagonally to the center lines between the columns and the rods of one belt course crossing the rods of the other belt course, and hollow tile positioned in the spaces bounded by the crossing belt courses of rods, the rods extending between diagonally placed columns of adjacent pairs exceeding in cross sectional area the rods of the belt courses in the remaining area of the slab.

5. A monolithic flat slab free from support along its several margins and sustained by columns the couples of which are spaced equidistantly embodying at least two belt courses of rods positioned in crossing relation and in the material of the slab substantially below the neutral axis and in the tension chord thereof, the individual rods of each belt course being positioned diagonally to the center lines between the columns and the rods of one belt course crossing the rods of the other belt course, the rods in the respective belt courses extending on the longer diagonal lines between opposite columns of adjacent pairs being composed of heavier material than the individual rods in the areas of the slab extending on the center lines between the columns.

6. A monolithic flat slab free from support along its several margins and sustained

by columns the couples of which are spaced equidistantly embodying at least two belt courses of rods positioned in crossing relation and in the material of the slab substantially below the neutral axis and in the tension chord thereof, the individual rods of each belt course being positioned diagonally to the center lines between the columns and the rods of one belt course crossing the rods of the other belt course, the rods in the respective belt courses extending on the longer diagonal lines between opposite columns of adjacent pairs being composed of heavier material than the individual rods in the areas of the slab extending on the center lines between the columns, and metallic mats positioned in the compression chord of the slab, one mat over each column, for taking care of the negative bending moment of the slab.

7. A monolithic flat slab supported solely on columns and initially stiffened by two belt courses of rods extending diagonally to the center lines between the columns and positioned in crossing relation to each other and in the material of the slab below the neutral axis thereof, the aggregate area of the rods being increased on the longer diagonal lines between diagonally opposite columns of adjacent pairs of columns.

8. A monolithic flat slab supported solely on columns and initially stiffened by two belt courses of rods extending diagonally to the center lines between the columns and positioned in crossing relation to each other

and in the material of the slab below the neutral axis thereof, the rods extending between diagonally opposite columns in adjacent couples of columns being heavier than the individual rods in the remaining area. 40

9. A monolithic flat slab supported solely on columns and initially stiffened by at least two belt courses of rods positioned in the material of the slab below the neutral axis thereof, and said rods of the belt courses extending diagonally to the center lines between couples of columns, the rods of one belt course crossing the rods of the other belt course to produce spaces rhomboidal in shape and the rods in each belt course which extend on the longer diagonal between diagonally placed columns of adjacent couples being heavier than the individual rods in the belt courses throughout the remainder of the slab, the heavier diagonal rods in one belt 50 course crossing the similar heavier rods in the other belt course. 55

10. A monolithic flat slab supported solely on columns and provided with two belt courses of rods below the neutral axis of the slab and arranged for the rods of one belt course to cross the rods of the other belt course throughout the area of the slab, and additional belt courses or short rods extending diagonally between the columns and positioned parallel to the rods of the first named belt courses. 60 65

In testimony whereof I have hereunto signed my name this 29th day of May, 1918.

KARL R. SCHUSTER.
